Attorneys

UNITED STATES PATENT OFFICE.

FRED W. ZINK, OF DETROIT, MICHIGAN, ASSIGNOR TO KALES STAMPING COMPANY, OF DETROIT, MICHIGAN, A CORPORATION OF MICHIGAN.

MIRROR SUPPORT.

Application filed June 5, 1922. Serial No. 565,842.

To all whom it may concern:

Be it known that I, FRED W. ZINK, a citizen of the United States of America, residing at Detroit, in the county of Wayne and State of Michigan, have invented certain new and useful Improvements in Mirror Supports, of which the following is a specification, reference being had therein to the accompanying drawings.

10 This invention relates to mirror supports and more particularly to devices for supporting rear view mirrors on vehicles.

The invention consists in the structural features and arrangement of parts herein-15 after described.

In the drawings:—

Figure 1 is a side view of the improved support;

Figure 2 is a top view thereof;

20 Figure 3 is a longitudinal sectional view taken on line 3—3 of Figure 1;

Figure 4 is a cross section on line 4—4 of Figure 3.

In these views the reference characters 25 A and A' designate a pair of complementary sheet metal stampings which form an elongated arm, the members A and A' co-acting at one end to clamp a rigid support B which may be either a bracket or a portion of a 30 windshield frame or standard and coacting at their other extremity to clamp a ball head D formed on the free end of a short arm E secured to a mirror carrying plate F. The members A and A' have complementary 35 semi-cylindrical portions for engaging the bracket B and at their other end have apertures E' to partially receive the head D, slots G being extended into said apertures to allow the arm E a wider range of angular 40 movement. The opposite edges of the members A and A' are flanged toward each other, as indicated at H and a clamping engagement between said edges is maintained

by bolts I. The parts A and A' are slightly bent at a point intermediate the two bolts 45 I adapting said plates to fulcrum one upon the other at said point J, as best seen in Figure 3, the bolts I serving to reduce the angle between the opposite end portions of said plates to clamp the latter upon the support 50 B or the ball head D. The marginal flanges J in addition to concealing the major portion of the ball head D tends to give the two part support an appearance of solidity.

What I claim as my invention is:—

1. A device of the class described comprising cooperating stampings having terminal clamping portions, said stampings also having edge flanges extending inwardly toward each other, said stampings and flanges being correspondingly bent inwardly at a point intermediate the ends thereof, and clamping members extending through the outwardly extending portions of said stampings upon opposite sides of said bends 60 for causing said stampings to fulcrum upon the flanges thereof at the bends and for adjusting said terminal clamping portions.

2. A device of the class described comprising cooperating stampings having complementary semi-cylindrical portions at one end for engaging a bracket and at the other end having aligned apertures to partially receive a ball member, said stampings also having edge flanges extending inwardly toward each other, said stampings and flanges being correspondingly bent inwardly at a point intermediate the ends thereof, and bolts extending through the outwardly extending portions of said stampings adjacent 70 to the ends thereof for causing said stampings to fulcrum upon the flanges thereof at the bends and for adjusting the ends thereof.

In testimony whereof I affix my signature:

FRED W. ZINK.
